United States Patent Office

Des. 184,536
Patented Mar. 3, 1959

184,536

PENDANT

Otto Rachmuth, New York, N. Y.

Application June 16, 1958, Serial No. 51,367

Term of patent 3½ years

(Cl. D45—17)

Fig. 1 is a front view of a pendant showing my new design;

Fig. 2 is a rear view thereof;

Fig. 3 is a front view thereof with the hingeable cover raised at a right angle to the base;

Fig. 4 is a sectional view taken through line 4—4 of Fig. 3;

Fig. 5 is a side view of the pendant shown in Fig. 3 with the hingeable cover in open position at right angle to the base.

I claim:

The ornamental design for a pendant, substantially as shown.
